Primary Examiner — Angela J Lee(74) *Attorney, Agent, or Firm* — Maine Cernota & Rardin(57) **CLAIM**

The ornamental design for a dual linear LED light, as shown and described.

DESCRIPTION

FIG. 1 is a top view of a dual linear LED light, showing our new design;

FIG. 2 is a bottom view thereof;

FIG. 3 is a rear view thereof;

FIG. 4 is a left view thereof;

FIG. 5 is a front side view thereof;

FIG. 6 is a back side view thereof; and,

FIG. 7 is a front, top and right side perspective view thereof. The figures are shown broken away to indicate that no particular length is claimed.
